SPARK PLUG

Hector Rabezzana, Flint, Mich., assignor, by
mesne assignments, to General Motors Corpora-
tion, Detroit, Mich., a corporation of Dela-
ware

Application June 22, 1933, Serial No. 676,996

3 Claims. (Cl. 123—169)

My invention relates to spark plugs for internal combustion engines, of the usual type where-
in a central electrode extends through a passage
in an insulator made of porcelain or equivalent
ceramic material, and which insulator is assem-
bled within the external metallic shell of the
plug; and the object thereof is to provide cer-
tain central electrode and insulating member
features whereby the insulating member is
strained less, and is less likely to be broken dur-
ing the assembling of the central electrode there-
with and the securing of it in place, than has
heretofore commonly been the case in spark
plugs.

15 A further object of my invention is to provide
a spark plug with insulating member and central
electrode features whereby a more rapid and
effective dissipation of heat therefrom and to the
metallic shell of the plug occurs than has here-
tofore been the case in spark plugs having similar
central electrode features; and with features
wherein such expansion of the central electrode
(due to the heating thereof by burning gases
within the engine cylinder) as cannot be prevent-
ed will not injure the insulating member, as by
setting up strains therein acting to crack or
otherwise injure the same.

With the above and other objects of invention
hereinafter appearing in view, my invention con-
sists in the improved central electrode and in-
sulating member features illustrated in the ac-
companying drawing and hereinafter described
and claimed; and in such modifications and va-
riations thereof, within the scope of the concluding
claims, as will be obvious to those skilled in
the art to which my invention relates.

In the drawing wherein the preferred form of
my invention is illustrated:

Figure 1 is a view showing a section upon a
40 longitudinal central plane, of a spark plug where-
in the features in which my invention consists
are present.

Figure 2 is a similar view, the shell of the plug
being omitted, showing my invention in a slight-
45 ly modified form. Both figures show the parts
about three times their actual size.

Referring now to the drawing for a more com-
plete understanding of my invention, the num-
eral 5 designates the external metallic shell or
50 casting of a spark plug; and 6 the insulating mem-
ber of porcelain or equivalent material which is
secured within the shell in any of the ways com-
monly employed in spark plugs for that purpose.
The insulating member in the preferred form of
55 my invention illustrated has an enlarged central

portion for convenience in securing it in place
within the outer shell of the plug although my
invention is not limited to an insulating member
having that feature, nor to a plug wherein the
insulating member is secured within the shell 60
in the particular manner illustrated.

The insulating member has an internal ledge
7 located, preferably, within the enlarged central
part thereof; an electrode passage 8 leading from
said ledge to the inner end thereof; and a larger 65
passage 9 extending from said ledge to the outer
end of the insulating member. This last pas-
sage is provided with an internal thread or equiv-
alent feature whereby a terminal electrode and
holding member 10 may be interlocked with the 70
insulating member in a positive manner and held
in place in said larger upper passage, and if as
shown an internal screw thread is employed for
that purpose the passage may be threaded
throughout its length as shown in Figure 1, or
75 at its inner end only as shown in Figure 2. In
fact the particular manner in which the mem-
ber 10 is interlocked with the insulating member
6 may be varied so long as the means whereby
such interlocking is accomplished is within the 80
enlarged upper passage 9 when the parts are
assembled.

The numeral 11 designates the central in-
sulated electrode of the plug, the same having an
enlarged head 12 at its inner end and which 85
head rests upon the ledge 7. This electrode ex-
tends through the passage 8 and fits closely
therein, the passage being larger than the elec-
trode only to an extent sufficient to permit the
electrode to be conveniently assembled with the 90
insulating member. The electrode is loose in
the passage, that is no cement is present between
it and the interior wall of the passage; from which
feature it results that the electrode is free to
expand independently of the insulating member 95
as it becomes heated, and that expansion and
contraction thereof does not subject the inner
end of the insulating member (which expands
very much less than the metallic electrode) to
strain as would be the case if the electrode was 100
cemented in place within the passage through
which it extends.

The inner end of the terminal and holding
member 10 engages the head 12 when the parts
are assembled and holds said head in engage- 105
ment with the ledge 7, and the electrode 11 in
place in the passage 8. A small quantity of ce-
ment is commonly supplied to the passage 9
after the electrode is put in place and which,
when the terminal member is in place, provides a 110

seal at 13 about the head and the lower end of said member. Some of this cement will be forced into the interstices between the threads at the lower part of the member 10 and the internal threads 5 of the passage 9 (or between the parts of whatever form of interlocking elements are made use of) as the terminal and holding member is moved into its assembled position, thereby providing a more perfect and effective seal; and cement may 10 be thereafter supplied, as shown at 14, to the space between the reduced upper part of this member and the interior of the passage 9; this last cement, if present, being supplied after the inner end of said member has been cemented in 15 place as hereinbefore explained. The outer end of the member 10 is threaded as shown at 15 to receive the usual terminal nut for connecting an electrical supply cable to the inner electrode of the plug, and the inner end thereof is shown as 20 rounded at 16 to avoid side thrust upon the head 12 if, as sometimes happens, the axes of the passages 8 and 9 are not parallel and in alignment with one another. The lower end of the member 10, though in contact with the head so as to 25 provide a metallic conducting path for a current of electricity, is not continuous with the lower electrode, from which it follows that the assembling of the parts will not subject the insulating member, particularly the inner end thereof, to 30 strain tending to break or otherwise injure the insulator.

In the form of my invention illustrated in Figure 2, the passage 17 is threaded only at its inner end, and the terminal and holding member 18 is 35 tubular, and has holes or slots 19 at its lower end; and after the electrode and the holding member have been assembled a suitable cement is supplied under pressure to the interior of said member, which cement flows through the slot 19 and rises 40 between the threads or equivalent interlocking elements and forms a seal 20 between the holding and terminal member and the passage 17 through which it extends. In this form of my invention the outer end of the member 18 is shaped to receive the spring clip of a supply cable instead of 45 threaded to receive a nut as in Figure 1.

In the preferred form of my invention illustrated the head 12 of the electrode 11 lies within the enlarged central part of the insulating member 6 as does also the inner part of the member 10 (or 18) which is in direct and intimate contact with the interior of the passage 9 (or 17), and the two are in direct metal to metal contact. It therefore follows that heat derived from the 50 burning gases and flowing along the electrode 11 is conducted to comparatively massive metal parts, and that a large part thereof is distributed throughout the massive central part of the insulating member and flows to the shell of the plug and is dissipated to the atmosphere and to the head and water jacket of the engine. The features, therefore, wherein my invention consists 55 secure a more effective conduction of heat from the inner electrode element, and a more rapid dissipation thereof to the shell of the plug than has heretofore been secured in spark plugs of the type to which my invention relates.

In the making of spark plugs the porcelain or 60 equivalent material insulating members are made into their final shape, and the passages 8, 9 and the ledge 7 are provided, before the members are glazed and fired. The material being quite soft it follows that the passages are often not perfectly formed, and are not always parallel and in 65 alignment; and these and other imperfections are

commonly increased rather than remedied during the firing process necessary to accomplish vitrification of the insulating members. Again and if, as is often the case, the terminal and holding member and the electrode are integral with one another, or if the electrode is welded to the terminal member, the assembly thus produced is likely to be more or less crooked or otherwise out of shape as when the axes of the two do not coincide. Thus and unless the parts approach very nearly 80 to perfection the assembling thereof is more or less difficult, and is often accompanied by bending of the metallic electrode and in the setting up of stresses which often break the insulator; this injury to or destruction of the insulator often occurring after the plug is finished as the strains produced may not be followed by immediate failure of the insulating member. A quite common way of attempting to avoid strains in the insulating member has been to make the passage for the lower end of the single piece central electrode structure much larger than the electrode; but this necessitates the filling of the passage around the same with cement thus introducing a condition 85 wherein longitudinal expansion of the electrode, due to heating thereof when the plug is in use, is liable to break the lower end of the insulating member; because, as will be appreciated, the material of the insulating member has a negligible coefficient of expansion and expands little if at 90 all, while the metallic electrode expands appreciably when the plug is heated by the burning gases within the combustion chamber of the engine.

In my invention and because the lower part of the central electrode structure is independent 110 of the upper part, the two may be assembled in passages which may be considerably out of alignment or otherwise lacking in perfection, without straining either electrode part or setting up stresses in the insulating member. Furthermore 115 and as will be appreciated, the passage for the lower electrode proper (the part 8) may be made of lesser diameter than heretofore, in fact only sufficiently larger than the electrode to permit the same to be put in place, thus making it unnecessary to surround such lower part with cement and avoiding injury to the insulating member by longitudinal expansion of said electrode as the plug becomes heated; and the fact that a comparatively short length only of the terminal 125 and holding member 10 (or 18) is threaded and rigidly interlocked with the insulating member lessens the liability to injury at this part of the insulator due to such expansion as may occur in said short length of the member 10 (or 18), due 130 to the heating of such part by conduction from the head 12 of the electrode 11. As a matter of course the inner threaded end of the terminal and holding member 10 (or 18) does not attain anything like the temperature of the electrode 11, 135 because the greater part of the heat is dissipated to the plug shell and engine structure; but nevertheless a decided advantage as regards the avoidance of strains in the insulating member is secured by making this threaded part short as 140 compared with the total length of said member.

Having thus described and explained my invention I claim and desire to secure by Letters Patent:

1. In a spark plug, an insulating member having an enlarged central portion, an internal ledge within said enlarged portion, a passage leading from said ledge to the inner end of said insulating member, and a larger internally threaded passage leading from said ledge to the outer end 145

of said insulating member; an electrode extending through said first-mentioned passage and having an enlarged head which rests upon said ledge; and a threaded terminal and holding member extending through said larger passage, and the lower end of which is rounded and engages the head aforesaid to hold said electrode in place.

2. In a spark plug, an insulating member having an internal ledge, a passage leading from said ledge to the inner end of said insulating member, and a larger internally threaded passage leading from said ledge to the outer end of said insulating member; an electrode extending through said first-mentioned passage and having an enlarged head which rests upon said ledge; and a tubular threaded terminal and holding member extending through said larger passage, and the lower end of which engages the head aforesaid to hold said electrode in place.

20

3. In a spark plug, an insulating member having an internal ledge, a passage leading from said ledge to the inner end of said insulating member, and a larger internally threaded passage leading from said ledge to the outer end of said insulating member; an electrode extending through said first-mentioned passage and having an enlarged head which rests upon said ledge; a tubular terminal and holding member extending through said larger passage and abutting against said head to hold said electrode in place; and means upon said terminal and holding member and within said larger passage adapted to interlock, to thereby secure said member in place within said larger passage.
